RADIO SPEAKER CONTROL STRUCTURE AND
CIRCUIT FOR USE WITH AUTOMATIC
TUNING DEVICES FOR RADIO RECEIVERS

William L. Dunn, Chicago, Ill., assignor to Belmont Radio Corporation, Chicago, Ill., a corporation of Illinois

Application January 6, 1938, Serial No. 183,577

13 Claims. (Cl. 250—20)

My invention relates in general to radio control apparatus and more in particular to means for selectively rendering the loud speaker of the radio receiver inoperative when using the control apparatus to tune the radio receiver and rendering the loud speaker operative while presetting the adjusting portions of the control apparatus to subsequently provide for tuning the radio receiver to predetermined control positions. The invention is particularly applied to so-called automatic control apparatus where the frequency controlling means of such apparatus is automatically operated to a predetermined control position or broadcast station setting. One commercial application of the invention is on control apparatus for a radio receiver including cams and levers such as is shown in the copending application of Alexander W. Plensler Serial No. 170,070. It is understood, of course, that the application of this invention is not limited to this particular type of mechanism.

In any tuning apparatus for radio receivers where the actual frequency control is automatically accomplished by pressing a lever, a button or any of the other various means now employed, the operator normally makes no change in the speaker volume at the same time the automatic tuning is being accomplished. As a result, there is objectionable noise in the speaker as the control apparatus passes through various frequencies in being tuned to the desired predetermined station. This noise is not only objectionable to the ear, but in receivers having high power output, the peak voltages created by rapidly tuning through powerful stations is likely to damage the loud speaker of the receiver. This is an old problem in the automatic tuning art, but the solutions to this problem heretofore provided are ordinarily expensive and not adapted to all types of automatic control apparatus. The present invention utilizes the elements of the control apparatus itself for silencing the loud speaker during automatic tuning and likewise provides for temporary operation of the speaker in the complete tuning operation merely while presetting adjustments in the automatic control apparatus are being accomplished. In this respect, therefore, my invention contemplates a system for selectively operating the loud speaker of a radio receiver during all operating steps for an automatic tuning device so that the operation of such device will not be objectionable, yet will have the speaker available when it is necessary to listen to station tuning to insure a peak setting for the control apparatus at a predetermined station.

It is an object of my invention to provide a simplified and improved speaker control system for use in connection with an automatic tuning device for a radio receiver.

A further object is to provide such a device which may readily adapt itself to automatic tuning structure and in fact utilize some of the elements of such structure for the operation of the system so that a minimum number of parts will be required.

A still further object is the provision of such speaker control apparatus particularly adapted to automatic tuning apparatus wherein the tuning apparatus includes movable levers so arranged that the end point of travel of the levers in accomplishing automatic tuning is constant regardless of the arrangement of the movable control elements corresponding to predetermined station settings themselves.

One of the features of my invention is the provision of mechanism for accomplishing silent automatic tuning in a radio receiver.

A further feature is the provision of a speaker control system which renders the radio speaker non-operative during automatic tuning, yet permits the normal operation of said speaker while one or more of the tuning control members is adjusted to a predetermined station setting.

Other objects and features of my invention will be apparent from the following description taken with the drawings, in which:

Fig. 1 is a schematic illustration of some of the elements of an automatic tuning device using a cam and lever structure, with the circuit for the speaker control system of my invention similarly illustrated in connection with such mechanism.

Fig. 2 is a fragmentary view partly in section of the adjusting knob illustrated at the right-hand side of Fig. 1 together with the switch in connection therewith.

Fig. 3 is a more extensive schematic diagram of the circuit and elements in the speaker control system of my invention, showing a different muting connection with the control apparatus.

Fig. 4 is a fragmentary end elevation of adjusting mechanism and switch corresponding to that of Figs. 1 and 2, yet modified therefrom.

Fig. 5 is a fragmentary sectional view on the line 5—5 of Fig. 4.

Fig. 6 is a fragmentary front elevation partly in section of a modified embodiment of my invention applied to cam and lever tuning mechanism.

Fig. 7 is a schematic diagram of the embodiment of Fig. 6 on the line 7—7 of Fig. 6, in com-

bination with the circuit diagram for this embodiment.

In the embodiment of Fig. 1 a tuning condenser is illustrated at 10, secured to a tuning shaft 11, supported in frame plates 12 and 13. Frame plate 13 is broken away in Fig. 1 merely to prevent confusion with the switch in connection with the adjusting knob as will be herein-after more fully described, but in fact extends upwardly to carry the shaft 11 as seen in Fig. 2. The rotors in the condenser 10 are rotated upon rotation of the shaft 11 and the latter rotation is accomplished by moving a cam 14 by means of a pivoted lever 16. The cam 14 is normally stationary with respect to the shaft 11, but may be angularly adjusted relative to said shaft to change the station setting corresponding to such cam. This adjustment may be accomplished, as is more fully described in the above noted Plensler application, by means of a tuning and adjusting knob 17 carried on the end of the shaft 11 as shown more particularly in Fig. 2. Although this specific structure is not a feature of the present invention, Fig. 2 might be described briefly as illustrating the knob 17 keyed to a sleeve 18 on the rotary shaft 11. The cams 14 are normally retained stationary with respect to the shaft 11 by means of friction washers 19 on each side thereof and slidable sleeves 21 bearing against the washers 19 so that upon threadable adjustment of the cap screw 22, sleeves 18 and 21 press the cam and washer assembly in a left-hand direction as shown in Fig. 2 to bear against a rigid member (not shown) at the left-hand end of the cam assembly on shaft 11. As sleeve 18 slides in a left-hand direction the knob 17 is carried therewith to change its axial position and in turn act upon the switch arms of the demuting switch D as will be more fully described hereinafter.

As to the speaker control structure of my invention including the demuting switch D, and as illustrated in Fig. 1, an electrical connection 23 is provided between the metal cam 14 and one side as 24 of the speaker circuit, including the output transformer 26, the voice coil 27, and field coil 28, and the speaker diaphragm itself is illustrated diagrammatically at 29. In Fig. 1, the connection to the cam 14 is illustrated as leading directly to such cam, but it is understood that this may be accomplished by a stationary brush bearing against the shaft 11 which is electrically common to the cam 14, or by a wire connected to the end plate 12 which likewise is electrically common to the shaft 11 and cam 14. A pivot rod 31 is mounted in the end plates 12 and 13 and insulated therefrom by means of fibre bushings 32, or the like, and such pivot rod 31 supports one or more tuning levers 16 corresponding to the cam members 14. The rod 31 and lever 16 are each metal and an electrical connection is made from such rod 31 through the switch D by means of leads of 33 and 34 to wire 36 forming the opposite side of the speaker circuit from the wire 24.

It is apparent that connecting the wire 24 directly to the wire 36 would short-circuit the speaker circuit or, in other words, shunt out the voice coil 27. This short-circuiting or shunting out of the voice coil 27 is automatically accomplished when the lever 16 is depressed in the automatic tuning operation. The shunting circuit is from wire 24 through lead 23, through cam 14, through lever 16 and its pivot rod 31, through wire 33, through the normally closed switch D and through wire 34 to wire 36. It follows that

the speaker is muted during any automatic tuning operation, the muting becoming effective as soon as the lever 16 engages the cam 14 and ceasing as soon as the automatic tuning is complete and the lever 16 departs from the cam 14.

5

Presetting the cams

In presetting the cam 14 with respect to the tuning shaft 11 so that operation of the lever 16 will turn the tuning shaft to a predetermined position in order to tune the radio receiver to a particular frequency, the lever 16 is held in its fully actuated position as shown in dotted lines in Fig. 7, to hold the cam 14 in the position to which it will always be thrust by the lever 16, and the shaft 11 is loosened from the cam 14 by reducing the frictional pressure on the cam so that the shaft may be tuned to the frequency which the user desires to have correspond to this actuated position of cam 14. According to the muting operation as so far described, the contact of the lever 16 with the cam 14 would shunt out the voice coil 27 with the result that it would be impossible to tune the set by ear in order to select a particular station or obtain peak tuning for that station with respect to the actuated position of the cam 14. This would be an undesirable effect. In other words, it is desired that the actuation of the lever 16 should mute the speaker during automatic tuning operations but should not mute the speaker during actuation of this lever for the purpose of presetting the cams 14 on the shaft 11. Of course, the actual presetting itself is accomplished when the lever is in cam holding position as previously noted. It is to provide this differential muting effect that the switch D is provided, the function of this switch being to nullify the muting circuit during presetting of the cam 14. This switch could for convenience be called a demuting switch. Briefly stated, the switch D is normally closed to render the muting circuit effective when lever 16 engages cam 14, but is automatically opened by operation of the knob 17 in the presetting operation so as to render the muting circuit ineffective during that operation.

The details of the actuation of switch D are seen in Fig. 2. When the screw 22 is loosened in order to relieve the pressure from sleeves 18 and 21, spring pressure from one or more spring washers W in the cam assembly slides the sleeve 18 to the right and with it the knob 17. The contact arms themselves in the switch D could provide this sliding pressure, and with the knob in the extended position, the cams themselves will readily loosen with respect to the shaft 11 when the presetting operation is undertaken. The knob 17 engages contact spring 38 of switch D and normally holds it in engagement with contact spring 39 of switch D to close the muting circuit. When the screw 22 is loosened, however, the handle 17 moves to the right. This permits spring contact 38 to spring away from contact 39 and open the muting circuit, thus rendering the muting circuit ineffective. The loud speaker 29 may now function, and while cam 14 is held in its actuated position by lever 16, shaft 11 may be turned by knob 17 to tune in the desired station accurately. This presets the cam 14 with respect to the shaft 11. The spring washer W will act to hold this preset adjustment even though the lever 16 is released, since there will normally be several such cams 14 each having a lever 16 and only one lever should be actuated at once. When all of the cams 14 have been preset, the cap

75

screw 22 may be tightened, thus locking the cams 14 permanently in their preset positions and drawing the knob 17 in against the contact spring 38 to close the switch D. This restores the muting circuit to operative condition so that it will mute the speaker when the lever 16 is next operated.

Alternative muting connections

10. There are various places in which the muting circuit may be connected instead of being connected across the voice coil 27 as seen in Fig. 1. In Fig. 3, for example, it has been shown in full lines as being connected by the wires 23a and 34a to input lead 41 and ground connection 42. The effect of this is to short-circuit the input of the tube 43 to ground so that this tube is rendered inoperative and therefore no impulses are transmitted through the remainder of the set through 20 the speaker 29.

In dotted lines in this same figure the muting circuit is indicated as connected at an alternative position by wires 23b and 34b in the same manner to the input connection of output tube 44 and to ground so as to short-circuit the signal impulses at this point. From these examples it will be apparent that the muting circuit may be connected at a variety of points, the only requirement being that it be so connected as to directly 30 or indirectly mute the speaker 29.

Alternating demuting switch

With different forms of presetting arrangements different switches may be necessary for nullifying the muting circuit during presetting. One other presetting construction is shown in Figs. 4 and 5, in which the cap screw 22 is replaced by a threaded collar 46 to which a toothed wheel 47 is secured, the wheel 47 normally being free to rotate with the shaft 11a. When it is desired to loosen the cam 14, a lever 48 is depressed so as to cause a dog 49 on the end thereof to engage the teeth of wheel 47, thus locking the wheel. The shaft 11a may then be turned in any suitable manner as by knob 51 thereon and since the collar 46 and wheel 47 are now restrained from turning by the dog 49, the wheel 47 will unscrew with respect to the shaft 11a along the threaded portion thereof, thus releasing the pressure on the friction washers 19 and loosening the cam 14 sufficiently to permit the presetting adjustment thereof with respect to the shaft 11a as previously described.

The lever 48 is normally retained in a retracted position by a suitable spring 52. In such retracted position it engages the spring contact 38 of switch D, pressing it against the spring contact 39 and thus closing the switch D to put the muting circuit in an operative condition ready to mute the speaker when one of the levers 16 is operated. However, when the lever 48 is operated to permit presetting of the cams it releases the pressure from spring contact 38 and permits this contact to separate from the contact 39, thus rendering the muting circuit inoperative during the presetting operation. When the presetting is complete and the shaft 11a has been turned by the knob 51 to screw the collar 46 tight and lock the cams 14 in place, the lever 48 will be released, thus closing the switch D to return the muting circuit to its operative condition.

Restricted muting

In Figs. 6 and 7 a muting arrangement has been 75 illustrated which automatically cancels the mut-

ing effect at the end of each tuning operation as the tuning lever reaches its fully actuated position. This makes a separately actuated demuting switch unnecessary since the presetting of the cam always takes place with the lever fully actuated to hold the cam in its actuated position. The automatic cancelling of the muting at the end of each tuning operation has the additional advantage of restoring the set to operation even though an inexperienced user should hold the 10 tuning lever depressed.

In this form of the invention one muting connection 61 extends to a lug 62 carried by a screw 63 which is supported by but insulated from the frame member 13. Normally engaging the screw 15 5 63 is a demuting bar 64 which is pivotally carried by the pivot bar 31 which also carries the tuning lever 16. The demuting bar 64 is normally urged upwardly into engagement with demuting screw 63 by a suitable spring 66. When the lever 16 20 is depressed, however, it will, near the end of its stroke, strike demuting bar 64 and depress it so that its contact with demuting screw 63 is broken, its depressed position being shown in dotted lines in Fig. 7. It should be noted that the spring 66 25 must be insulated either from the demuting bar 64 or from the frame member by which it is supported, and in Fig. 7 it has been shown as insulated from a cross bar 67 by a rubber sleeve 68 to which it is secured. 30

The cross bar 67 and rubber sleeve 68 also serve as an insulated stop for the lever 16 in its normal position, any suitable means being provided for biasing the lever to this position. Of course, it is understood that such biasing means 35 and a suitable insulated stop could also be provided for the tuning lever 16 in Fig. 1. It may be mentioned that bars are used for the elements 64 and 67 rather than short lugs because there are usually five or more tuning levers 16, and the 40 elongated bars may serve them all.

In Fig. 7 the muting circuit which is closed when lever 16 strikes cam 14 extends from one side of voice coil 27 through lug 62, through screw 63, through demuting bar 64 to pivot bar 31 and 45 from this bar through lever 16, cam 14, shaft 11 and frame plate 13 to ground. Since the other side of voice coil 27 is also connected to ground, this muting circuit short-circuits the voice coil 27.

The dotted line 61' in Fig. 7 indicates an alternative connection for the muting lead 61 similar to the connection 23a or 23b of Fig. 3. With this connection the muting circuit would mute the speaker indirectly by short-circuiting the input side of the tube 44. 50 55

The screw 63 is so positioned as to hold the demuting bar 64 out of contact with the tuning lever 16 until the latter is approximately at the end of its stroke, perhaps $\frac{3}{2}$ of an inch from the end of its stroke. At this time the lever 16 60 breaks the contact between the demuting bar 64 and demuting screw 63, and hence opens the muting circuit and renders it ineffective so that as the cam 14 reaches the position desired, the speaker will again become operative and the desired program will be heard, or if it is desired to change the position of cam 14 on shaft 11 this may be accomplished by turning the shaft with a suitable knob, such as the knob 17 of Fig. 1, while holding the lever 16 depressed. a visual tuning indicator which shows peak tuning visually, the demuting switch D in Figs. 1 and 4 and the corresponding demuting switch formed by demuting bar 64 and screw 63 may be omitted, such demuting switches being necessary only to permit tuning by ear during presetting of the cam 14 on the shaft 11. Even with such visual tuning indicators, however, the arrangement of Figs. 6 and 7 is preferred since it 5
10 stores the receiving set to operation immediately upon completion of the tuning, even if the tuning lever be held depressed.

From the foregoing it is seen that an extremely simple muting circuit is provided which is suitable for use in combination with the exceedingly simple lever and cam type of automatic tuning devices, and that suitable means is also provided for rendering the muting circuit ineffective during presetting of the cams to permit tuning by 15
20 ear during such presetting of the cams to provide peak tuning at a preset position.

The disclosures of this application are illustrative and the invention is not to be limited by them. In fact, if modifications or improvements 25
30 are not at once obvious, they may be devised in the course of time to make additional use of the broad ideas taught and covered by this application. The claims are intended to point out novel features and not to limit the invention except 35
40 as may be required by prior art.

I claim:

1. A radio receiver system including in combination, a radio receiver circuit having a loud speaker therein, tuning means for said receiver circuit including a rotary shaft, a tuning member on said shaft normally stationary with respect to said shaft, but selectively adjustable with respect thereto, means for moving said tuning member and said shaft, circuit means including 5

8. A radio receiver system including in combination, a radio receiver circuit, tuning means for said receiver circuit including a rotary shaft, a tuning member on said shaft normally stationary with respect to said shaft, moving means for said tuning member and said shaft normally out of engagement therewith, a muting circuit including said tuning member and said moving means closed by engagement of the moving means with said tuning member to render the receiver circuit temporarily inoperative to reproduce received signals, and a demuting switch in said muting circuit for rendering the muting circuit ineffective even while said moving means is in engagement with said tuning member.

9. A radio receiver system including in combination, a radio receiver circuit, tuning means for said receiver circuit including a rotary shaft, a tuning member on said shaft normally stationary with respect to said shaft, moving means for said tuning member and said shaft normally out of engagement therewith, a muting circuit including said tuning member and said moving means closed by engagement of the moving means with said tuning member to render the receiver circuit temporarily inoperative to reproduce the received signals, and a demuting switch in said muting circuit for rendering the muting circuit ineffective even while said moving means is in engagement with said tuning member, said demuting switch being operated by said moving means at the end of its moving stroke.

10. A radio receiving system including a receiving circuit adapted to be tuned to different frequencies by means of a tuning shaft, a plurality of cams on the shaft normally locked on the shaft to rotate therewith but releasable at will for adjustment with respect to the shaft, a tuning lever for each cam adapted to be actuated to rotate the cam to a predetermined position whereby the receiving circuit may be tuned automatically to any one of a plurality of frequencies by selective actuation of the levers, a muting circuit for rendering the receiving circuit inoperative to reproduce signals during such automatic tuning connected through the actuating lever and the cam whereby the circuit is closed by the engagement of the lever on the cam, and a normally closed switch in the muting circuit including a bar positioned to be engaged for opening the switch by each of the actuating levers as it reaches the end of its stroke.

11. A radio receiver including in combination a radio receiver circuit, means for tuning said radio receiver circuit including a rotatable shaft and a movable control member thereon, an actuator for moving said control member, friction varying means acting on said control member to prevent or permit angular adjustment of said control member with reference to said shaft depending upon whether friction is applied to or removed therefrom, a muting circuit including said control member and said actuator therein and connected into said receiver circuit and including a demuting switch, with said switch being mounted in a position with reference to said friction

varying means whereby said switch is open to continuously maintain said muting circuit open when the friction is substantially removed from said control member and closed to maintain said muting circuit closeable when the friction is applied to said control member, with said muting circuit adapted to be closed when the demuting switch is closed upon engagement of said control member and said actuator.

12. A radio receiver including in combination a radio receiver circuit, means for tuning said radio receiver circuit including a rotatable shaft and a movable control member thereon, an actuator for moving said control member, friction varying means acting on said control member to prevent or permit angular adjustment of said control member with reference to said shaft depending upon whether friction is applied to or removed therefrom, said friction varying means including a knob unit on said shaft having threadable axially adjustable means therein for causing axial movement of said knob unit, a muting circuit including said control member and said actuator therein and connected into said receiver circuit, said muting circuit including a demuting switch mounted in a position with respect to said knob unit whereby said switch is open to continuously maintain said muting circuit open when the friction is substantially removed from said control member and said switch is closed to maintain said muting circuit closeable when the friction is applied to said control member, with said muting circuit adapted to be closed when the demuting switch is closed upon engagement of said control member and said actuator.

13. A radio receiver including in combination a radio receiver circuit, means for tuning said radio receiver circuit including a rotatable shaft and a movable control member thereon, an actuator for moving said control member, friction varying means acting on said control member to prevent or permit angular adjustment of said control member with reference to said shaft depending upon whether friction is applied to or removed therefrom, said friction varying means including an internally threaded toothed unit vertically carried on said shaft and operatively connected with said control member, and a pivoted lever for engaging said teeth of said internally threaded toothed unit for maintaining said unit fixed while rotating said shaft with reference thereto, a muting circuit including said control member and said actuator therein and connected into said receiver circuit, said muting circuit including a demuting switch mounted in a position in respect to said lever whereby said switch is open to continuously maintain said muting circuit open when said lever is in engagement with said teeth and said switch is closed to maintain said muting circuit closeable when said lever is out of engagement with said teeth, with said muting circuit adapted to be closed when the demuting switch is closed upon engagement of said control member and said actuator.

WILLIAM L. DUNN. 65
